(57) **CLAIM**

The ornamental design for a solar powered wireless backup camera, as shown and described.

DESCRIPTION

FIG. 1 is a front elevational view of a solar powered wireless backup camera showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof;

FIG. 8 is a rear perspective view thereof; and,

FIG. 9 is a front and right side perspective view thereof, shown in condition of use with a support disclosed in broken lines to illustrate an environment.

The broken lines showing a support in FIG. 9 represent environmental structure and form no part of the claimed design.
